INVENTOR

UNITED STATES PATENT OFFICE.

JOSEPH V. SMITH, OF PITTSBURGH, PENNSYLVANIA.

IMPLEMENT-HANDLE.

1,342,467.

Specification of Letters Patent.

Patented June 8, 1920.

Application filed May 13, 1919. Serial No. 296,818.

To all whom it may concern:

Be it known that I, JOSEPH V. SMITH, a citizen of the United States, and a resident of Pittsburgh, in the county of Allegheny and State of Pennsylvania, have made a new and useful Invention in Implement Handles, of which the following is a specification.

My invention relates to handles or hand-holds for agricultural implements, tools, utensils or the like and consists of an improved method of retaining grip members upon a handle frame. The object of the invention is to provide flange-like means preventing the separation of the grips from the handle and to avoid, as much as possible, reliance upon rivets, screws, etc., for maintaining the assembly.

I have illustrated my invention as applied to the D of an implement handle stem such as a shovel or pickax and in the accompanying drawings Figure 1 is a front elevation of the handle grip or D showing a small portion of the handle stem to the opposite end of which the shovel or other tool is attached; Fig. 2 is a vertical transverse section on line 2-2 of Fig. 1 and Fig. 3 is an end view of the D.

The D is formed of metal either cast or forged and its base 1 is provided with a socket 2 to receive the end of the handle stem 3 and be secured thereto by rivets or other fastenings 4. Integral with base 1 are the diverging curved sides 5 spaced apart at their outer ends and there connected and braced by a flat transverse rib 6, the D thus terminating in a substantially I shaped section as best shown in Fig. 3. On opposite sides of rib 6 are half round strips 7 of wood or other non-conducting material extending between sides 5 and secured to rib 6 by screws or rivets 8.

Sides 5 are undercut near their outer end as indicated at 9 in Fig. 3. The ends of strips 7 are shaped to fit this undercut and also the relative taper of sides 5. As a result of the tapered and undercut D surfaces and the corresponding shaping of the ends of strips 7, the latter can only be inserted from the top of the D and when assembled therewith are held against downward, longitudinal or transverse movement, leaving only a possible upward movement for the fastenings 8 to resist. Such construction prevents twisting or other undesirable

movement of strips 7 and safeguards the latter against splitting and undue wear.

In the usual handle, grip members are attached by rivets and most of the twisting or sliding tendencies of the grips must be withstood by the rivets. The rivets are of small diameter, bend easily and their small area wears away the sides of the holes in the grip members which allows undesirable free play of the latter. The grips often separate from the base by slipping over the rivet heads after wear or shrinkage. These disadvantages are removed in my construction which has a wide range of usefulness and is not limited to the type of handle illustrated.

I claim:

1. In a handle, a frame having a plane surface and flanges forming dihedral angles opposed to each other and having converging edges, said surface and flanges being adapted to receive a grip member and retain same against movement in all directions except one.

2. In a handle, a frame with surfaces forming opposed, dihedral angles and provided with a grip member held by said surfaces against movement in a plane traversing said surfaces; said angles having their respective edges converged to hold said grip members against movement along same in one direction.

3. A hand hold including spaced sides, a brace uniting said sides; said sides converging toward each other and recessed to form acute angles with said brace, and grip members secured to said brace and fitting between said converging sides and in said acute angles.

4. In a handle, a grip member having its ends converging across the width of the member and beveled across the thickness of the member, a frame to which said member is secured and which is provided with flanges converging and recessed to fit the converging and beveled ends of said member.

5. In an implement handle, a base adapted to be attached to a handle stem, spaced sides extending divergently from said base and from each other, a brace uniting said sides; said sides forming acute angles with said brace, and grip members secured to said brace and having ends fitting between said converging sides and in said angles.

6. In a hand hold, a socket adapted to

- receive an implement end of the handle stem, integral spaced sides extending from said socket, an integral brace spaced from said socket and uniting said sides, said sides being recessed to form acute angles with said brace and converging toward each other, and grip members secured to said brace and fitting between said converging sides and in said acute angles.
- 10 7. In a handle, a longitudinal member, transverse flanges at opposite ends of said member, converging in the direction of the

width of said member and each forming an acute angle with the side of said member, and a grip member adjacent said longitudinal member and having its ends converged to engage said flanges and each end beveled to fit in the angle between one of said flanges and said member. 15

In testimony whereof, I have hereunto 20
subscribed my hand this 6th day of May,
1919.

JOSEPH V. SMITH.
